GARMENT PAD TO CORRECT LOW SHOULDERS

Sol Drescher, Hewlett Harbor, and Harry Bryer,
New York, N. Y.

Application January 15, 1953, Serial No. 331,377

1 Claim. (Cl. 2—93)

This invention relates to garments and particularly to a pad used to improve the fit of ready-made jackets or coats.

Most persons have one shoulder lower than the other requiring ready-made garments to be altered to fit the individual customer. The effect of the low shoulder is to cause the material of the garment to bunch up and wrinkle either in the front or the back of the garment or in both the front and back on the lower shoulder side.

Alterations constitute one of the largest single items of expense for retail clothing merchants and also often cause undesirable delays in the delivery of the altered garment to the purchaser. The alterations now required to fit a low shoulder are especially expensive and time-consuming due to the complexity of the operation. It is present practice to fit the low shoulder by re-cutting and re-shaping the shoulder or by placing thick padding above the normal shoulder padding to raise the garment. Both of these methods are expensive and time-consuming and require the services of a skilled tailor. In addition, the method of adding extra shoulder padding is undesirable, since it results in a bunching effect at the shoulder and leaves a shoulder which may be easily misshapen by wear or during cleaning and pressing.

The present invention accomplishes the necessary alteration by using a pad which is easily and quickly inserted in the coat by inexperienced personnel. This allows the retail merchant to fit coats and jackets more inexpensively and more rapidly and to thus give the customer better service and to increase his sales.

The pad is furnished to the retail clothing merchant complete and ready to be slipped into the coat or jacket. The merchant merely trims the pad to the shape required for a particular fit and then stitches it inside the coat lining, as will be more fully described hereafter.

The pad is thin and elastic and will not bunch or crease. It requires only a few minutes' work by inexperienced personnel to fit a garment for a person having one shoulder as much as half an inch lower than the other. Since the pad has a large area and is relatively thin, the altered garment will be made to fit without any bulky padding effect being created, as occurs where the shoulder pad itself has been appreciably thickened to raise a low shoulder.

These pads are inexpensive to manufacture and the time saved by using the pad will be worth many times the cost of the pad to the merchant.

An object of the invention is to provide an inexpensive and simple way of fitting the shoulders of a garment using an alteration pad.

Another object of the invention is to provide a light-weight pad for use in the alteration of garments which is creaseless and elastic in all directions.

Another object of the invention is to provide a pad for the fitting of garments for low shoulders which will be simple to use, so that the fitting may be done by inexperienced personnel.

Another object of the invention is to provide a thin

2

pad for fitting the shoulders of ready-made garments without adding to the bulk of the original shoulder padding.

Another object of the invention is to provide an alteration pad with a stiffening layer which does not use stiff individual fibers or hairs.

Other and further objects of the invention will be obvious upon an understanding of the illustrative embodiment about to be described, or will be indicated in the appended claim, and various advantages not referred to herein will occur to one skilled in the art upon employment of the invention in practice.

A preferred embodiment of the invention has been chosen for purposes of illustration and description and is shown in the accompanying drawings, forming a part of the specification, wherein:

Fig. 1 is a plan view of the pad;

Fig. 2 is a sectional view on the line 2—2 of Fig. 1;

Fig. 3 is a rear view of a coat before the insertion of an alteration pad;

Fig. 4 is a rear view of a coat with an alteration pad inserted in the lining yoke;

Fig. 5 is a front view of a coat opened up to show the position of a pad inserted in the front lining; and

Fig. 6 is a front view of a coat opened up to show the position of a pad inserted in the yoke or back lining.

Referring to the drawings, Fig. 1 shows a pad 1 which is designed for insertion in the coat linings. The pad is of inexpensive construction and as shown in Fig. 2 consists of three layers. The two outer layers 2 and 4 are made of a soft padding material, such as cotton wadding, and the center layer 3 is a stiffening layer. The stiffening layer is preferably made of a resilient, creaseless, isoelastic and shrinkproof unwoven textile such as Pellon, which is manufactured by the Pellon Corporation, of New York city. A material such as this provides a pad which will fit snugly against the lining of the garment and which will at the same time conform to the shape of the garment. It will also pro-

vide a pad which will not retain any creases even though the garment is tightly folded across the pad. It also provides a pad which is isoelastic or which, in other words, resumes its original shape and size no matter in what direction it is stretched. This is due to the fact

that the properties of an unwoven textile are non-directional. Also, being isoelastic, the material may be cut in any direction so that the pad may be trimmed to any shape required for a particular garment. Woven stiffeners such as hair cloth, which are commonly used in garments, have resiliency in only one direction. When stressed in other directions, the hair cloth will be permanently stretched out of shape.

The layers of the pad are fastened together in any convenient manner such as by a thread 5, as shown in Figs. 1 and 2. Fig. 1 shows a zig-zag pattern of stitching but any convenient one may be used, or the layers may be glued together or clipped with small rust-proof staples or otherwise fastened together. The number of layers of material used may also be varied since the stiffening layer or the padding layers or both may be laminated, or the pad could be made with only two layers consisting of a stiffening layer and a padding layer.

Fig. 3 shows the characteristic wrinkles in the back of a coat caused by the excess material resulting when a person with a low shoulder wears a ready-made coat. Similar wrinkles may also occur in the front of the coat. Removal of these wrinkles is one of the more serious alteration problems confronting the retail clothing merchant. In place of re-cutting and re-building the whole coat shoulder or of placing a small thick pad at the shoulder seam 13, the pad 1 is inserted in the garment as shown in Fig. 4. This pad fits the low shoulder and

removes the wrinkles by raising the shoulder slightly but more importantly by providing a thin filler pad over the large area 6", 7", 8" and 9".

Fig. 6 shows a front view of a coat with the pad 1 inserted as in Fig. 4 to remove the wrinkles 11 from the back of the coat. A typical lining member or yoke 12, now being commonly used, is shown fitted in the coat back below collar 14. This yoke is made of two layers of cloth with a pocket-like space between layers, and extends as shown in Figs. 5 and 6 from the collar 14 around the arm hole 16 to the side seam 15. The pad 1 is inserted into the pocket of yoke 12 by opening one of its edge seams and slipping the pad between the two layers of the yoke. The pad is first trimmed to fit the yoke pocket and then as much more as necessary to provide the proper pad area to remove the creases 11. The pad will then have the shape shown in Fig. 6 with edges 6", 7", 8" and 9". After the yoke edge seam has been re-fastened, the pad 1 is stitched at several points to the yoke to hold it in place. The pad is preferably placed as shown in Fig. 6 with the edge 6" approximately an inch beyond the shoulder seam 13. Edge 8" follows around the edge of arm hole 16 to side seam 15. Edge 9" is fastened near side seam 15, and edge 7" is fitted along the inner edge of yoke 12.

Fig. 5 shows a front view of a coat with the pad 1 inserted behind the front lining to remove wrinkles in the front of the coat. A typical coat front is either fully lined or lined from the collar 14 to a point below the arm hole 16. In either case, the pad 1 may be slipped behind the lining and located as is indicated in Fig. 5. The edge 6' is placed approximately an inch beyond the shoulder seam 13. The edge 8' is trimmed to follow the front edge of arm hole 16 and the edge 9' is cut to fit near side seam 15. Edge 7' is cut to fit behind the lining and may be further trimmed to provide the desired pad area for the particular alteration required. After insertion, the pad is stitched at several points to the lining to keep it in place.

The pad may be used in a variety of garments such as men's or women's suits or topcoats. Where the rear lining is not made in the form of a yoke as shown at 12 in Fig. 6 but is a single-thickness half or full length lining, the pad may be shaped as desired and slipped behind the lining and stitched as is done when the pad is used with a front lining as in Fig. 5.

It will be seen that an improved alteration pad has been provided which can be used to make ready-made garments fit the individual purchaser. Use of this pad provides a simple, rapid and inexpensive way to make the necessary alterations of garments required by the variations in the garment buyer's figure, such as low shoulders.

The pad may be inserted by inexperienced personnel at the retail merchant's store. This will materially simplify the alteration problems of the merchant and will allow him to provide a less expensive and more rapid alteration service. The pad itself, being relatively thin and being both creaseless and elastic, will resist bunching and will remain inconspicuous no matter how the garment is hung or folded.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described our invention, we claim:

A flat elongated alteration pad of substantially uniform thickness having one longitudinal edge concavely curved and the other longitudinal edge convexly curved, said longitudinal edges being connected at one end by a substantially straight transverse edge extending at substantially right angles to the longitudinal edges, the other ends of the curved edges being connected by a second end edge which extends at substantially right angles to the direction of the first mentioned end edge, the first mentioned end edge being adapted to be fitted into the shoulder seam of a garment, the concavely curved edge being adapted to be fitted into the rear seam of the sleeve, and the second named end edge being adapted to be fitted into the side seam below the sleeve opening of the garment, said pad comprising an inner stiffening layer and two outer layers stitched together in substantially parallel relationship to each other, said inner layer being relatively thin and being formed from a substantially creaseless, shrinkproof, grainless, unwoven fibrous textile fabric which is resilient in all directions, said outer layers being formed of a soft padding material thicker than the said inner layer, and the width and length of said pad being many times the thickness of said pad, whereby it may cover a large surface area of a garment without adding appreciably to the garment thickness.
